UNITED STATES PATENT OFFICE.

HENRY P. FIELD, OF BERWICK, PENNSYLVANIA, ASSIGNOR TO AMERICAN CAR AND FOUNDRY COMPANY, OF NEW YORK, N. Y., A CORPORATION OF NEW JERSEY.

MINE CAR.

Application filed April 9, 1926. Serial No. 100,872.

In the drawings:

Figure 1 is a plan view of a mine car constructed in accordance with the invention;

Fig. 2 is a side elevational view of the mine car shown in Fig. 1;

Fig. 3 is a sectional view along the line 3-3 of Fig. 1;

Fig. 4 is a sectional view along the line 4-4 of Fig. 1;

Figs. 5 and 6 are transverse sections of the mine car showing modified constructions of the side sills, side floors and side walls;

Fig. 7 is a sectional view along the line 7-7 of Fig. 8;

Fig. 8 is a plan view of a portion of the car showing a modified bumper, and

Fig. 9 is a sectional view showing a modification having the axle housing secured to the sill.

One object of the invention is to provide a mine car that shall have a very low height to permit operation in mines having a low-height seam and to lighten the labor of filling it and that shall have the floor thereof below the wheel axles and housings over the axles so constructed as to enable the complete clearing of the material carried by the car when effecting the so-called end dumping.

Another object of the invention is to provide a center bumper mine car that shall have plate girder side sills connected by ties which, below the wheel axles, support a floor having a longitudinal buffer beam as a part thereof and that shall have a coupler member suitably connected to the buffer beam.

In a mine car it is a very desirable feature to have the height thereof very low for service in mines where the coal seam is not very thick. Moreover, it is apparent a low-height car materially lessens the labor of loading it and provides a low center of gravity so as to insure better operating qualities. A mine car constructed in accordance with this invention has the central floor thereof positioned below the wheel axles and supported on the side sills and ties connected to the side sills.

Referring to Figs. 1, 2, 3 and 4, a mine car is illustrated comprising wheels 1, which are mounted upon axles 2, and plate girder side sills 3 which are mounted on journal boxes 4 carried by the axles 2. In Fig. 3 of the drawings the side sill 3 is shown provided with an inwardly extending bottom

flange 5 and an outwardly extending top flange 6. To the bottom flange are secured the belts 7 by means of rivets 8. The belts 7 not only serve to connect the bottom flanges of the side sills but also serve as braces for the side floor sections and the side walls of the car.

A plate 9 is bent on each side of the car to form a side wall section 10 and a side floor section 11. The plate is connected to the top flange of the sill by rivets 12 and to the belts 7 by rivets 13. The side floor section 11 is inclined from the top flange of the side sill to a point beyond the wheels 1 and intersects the wheels, as indicated in Fig. 3 of the drawings. Suitable openings are provided in the sloping portions of the side floors to prevent interference with the wheels and hoods 15 are provided for covering the openings. The openings in the side floors 75 and the hoods are made of such size as to permit the removal of the wheels from any axle without disturbing the position of the axle. The portion of the side floor beyond the sloping section is formed horizontal and 80 the portion 10 of the plate 9 which forms the side walls of the car is provided with a turned over part 16 at the top thereof. The belts 7 do not follow the contour of the side 85 sills and side floors, as indicated in Fig. 3 of the drawings, but extend from the bottom side sill flanges to a point along the inclined portion of the side floors 11 and then follow the contour of the side floors and side walls.

A longitudinal buffer beam 17 having bottom flanges 18 thereon is carried by the belts 7 which serve as ties between the side sills 3. The flanges 18 of the buffer beam are secured to the belts 7 by rivets 19. The top portion of the buffer beam is secured to the axle 95 housings 20 by means of rivets 70. The axle housings extend between the side sills 3 to cover the wheel axles. The front portion 21 of each housing very closely follows the outline of the axle whereas the rear portion 22 thereof has a gradual slope downwardly to the floor as is indicated in Fig. 2 of the drawing, to insure the clearing of the material from the car when the rear end of the car is elevated for dumping purposes. Between 105 the housings 20 and the belts 7 on each side of the buffer beam 17 are mounted wooden planks 23 and 24. The planks 23 and 24 are cut away to accommodate the flanges 18 on the buffer beam and the bottom flanges 5 on 110

the side sills 3. The rivets 8 and 19 for connecting the belts 7 to the side sills and the buffer beam to the belts are countersunk in order not to interfere with the sliding of the planks 23 and 24 in position under the wheel axles. Removable bolts 25 are provided between the front flanges on the axle housings 20 and strips 26 extending between the side sills below the planks 23 and 24 and the buffer beam. The bolts 25 in the rear flange of one of the housings 20 are connected to a belt 7 in place of a strip 26 as shown in Fig. 2 of the drawings. The rear flange of the front housing 20 is also connected by bolts 25 to a strip 26. Bolts 27 are also provided for connecting the strips 28 mounted on the central flooring and the belts which are located on each side of the forward wheel axle. The bolts 27 and 25 may be easily removed when it is necessary to renew the planking in the central floor.

In Fig. 9 of the drawing it will be noted the wheel housing 20 is provided with a flange 30 which is connected to the side sill 25 by means of bolts 31 and 31^a. The bolt 31^a is set in a countersunk hole in order to avoid interference with the journal boxes. When the axle housings 20 are constructed as shown in Fig. 9 of the drawings, the side sills are not only connected by the belts below the flooring but are tied together by the axle housings above the flooring.

The front end of the car is provided with a door 32 mounted on brackets 33 and 34. The bracket 34 is secured to the bracket 33 and the bracket 33 is pivotally mounted on the side walls of the car by means of bolts 35 as shown in Figs. 1 and 2 of the drawings. Each bolt 35 is supported on the side walls 30 of the car by means of bracket 36 and one end of a belt 7. During the raising of the rear end of the car for dumping purposes the door 32 is swung upwardly. The rear end of the car is raised a height sufficient to permit the carried material to slide freely over the axle housings.

A plate girder end wall 37 is formed at the rear end of the car. Such plate girder end wall is shaped to conform to the outline 50 of the side walls and side sills of the car and is provided with a bottom flange 38 positioned above the buffer beam and the planks 23 and 24. Such flange 38 is connected to the belt 7 at the end of the car by means of the removable bolts 39. Flanges 40 are also provided on the end wall to engage the side floor portions and the side wall portions of the plate 9. Such flanges 40 are connected to the end belt and the plate 9 by means of rivets.

The ends of the buffer beam and the ends of the planks forming the central floor extend beyond the ends of the car body to form a bumper. A filler block 42 is mounted 65 above the ends of the planks and the ends of

the buffer beam, as shown in Fig. 4 of the drawings, and a top bumper plate 43 and a bottom bumper plate 44 connected by an end plate 45 enclose the filler block and the ends of the buffer beam and a portion of the floor 70 planking. A coupler member 46 projects downwardly through a slot 47 formed in the top bumper plate 43 and a slot formed in the filler block 42 to the top of the buffer beam 17 and is connected thereto by rivets 75 48. Suitable openings are provided in the coupler member 46, the plates 43 and 44 and the buffer beam for the insertion of a coupling pin. In the construction above described the plates 43 and 44 of the bumper extend to the belt at the end of the car but are not directly connected thereto. Moreover such plates 43 and 44 do not extend completely over the width of the central floor, as indicated in Fig. 1 of the drawings 85 and removable bolts 49 are provided for connecting the plates 43 and 44 to the planks of the central floor.

A sloping bumper sheet 52 extends over the filler block 42 at the door end of the car 90 in order to insure clearing the car of the carried material during the dumping operation. The lower end of the sheet 52 is connected to the central floor by removable bolts 53. The bolts 53 are secured to a strip 54 95 positioned below the buffer beam and the floor planking. The upper end of the sheet 52 extends over the end of the filler board and is connected to an end belt 7 by means of removable bolts 55. A strip 56 below the 100 end of the sheet 52 extends across the filler block 42.

Referring to Figs. 7 and 8 of the drawings, a modified bumper construction is illustrated. In the modified construction it 105 will be noted the portions of the bumper sheet 57-58, which are integral with the end sheet 59, extend over the belt 7 at the end of the car as shown in Fig. 7 of the drawings. Consequently the bolts 55 in 110 such constructions also serve to secure the bumper plate portions 57 and 58 directly to a belt 7. The top and bottom of the bumper plates 57-58 also extend across the planks of the central flooring as indicated 115 in Fig. 8 of the drawings. A corner of the lower plate 58 adjacent each side sill is cut away at 60 to receive the end portions of the flanges 5 on the side sills. End portions of the flanges 18 on the buffer beam 17 are 120 cut away as shown in Fig. 8 of the drawings and the bottom plate 58 is cut away as at 61 to receive the flanges 18 of the buffer beam. A bumper sheet 52 similar to the bumper sheet shown in Figs. 1 to 5 inclusive, 125 is provided in the modification shown in Figs. 7 and 8.

Referring to Fig. 6 of the drawings a modification of the invention is shown wherein the side sill, the side floor portion 130

and the side wall on each side of the car are formed from a single plate. In Fig. 6 like reference numerals have been used to designate similar parts to those shown in Figs. 1 to 5, inclusive. The single sheet 62 shown in Fig. 6 includes the side sill 3 which is integral with the side floor and the side walls 10. The side sill is not provided with an upper top flange 6 as shown in Fig. 3. However, a bottom inwardly extending flange 66 is provided.

Referring to the modification shown in Fig. 5 of the drawings, a wooden side wall 63 is shown connected to the belts 7 by means of bolts 64. The side floor portions and side sills are similar in shape to the side floor and side sills shown in Fig. 6 and are formed from one sheet of metal. The sheet 65 forming the side floor portions and the side sills 20 is provided with a bottom flange 66 similar to the flange 5 shown in Figs. 3 and 6 and is provided with a flange 67 extending back of the wooden side wall 63 and connected to the belts by the bolts 64.

25 What is claimed is:

1. In a mine car, sills, wheel axles, ties between said sills, a longitudinal buffer beam supported on said ties and located below the wheel axles, and coupler members connected 30 to said buffer beam.

2. In a mine car, sills, wheel axles, ties between said sills, a longitudinal buffer beam supported on said ties and located below the wheel axles, and housings for the wheel axles 35 above said buffer beam, said housings being connected to said sills.

3. In a mine car, sills, wheel axles, ties between said sills, a floor having a longitudinal buffer beam supported on said ties and located below the wheel axles, coupler members connected to said buffer beam, and housings for the wheel axles, said housings having a gradual slope towards one end of the car for preventing the housings interfering 45 with the dumping of the car contents.

4. In a mine car, wheel axles, side sills having inturned flanges formed at the bottom thereof, ties between said sills, a floor located below the wheel axles and mounted 50 on said flanges and ties, a longitudinal buffer beam forming a part of said floor, and coupler members connected to said buffer beam.

5. In a mine car, wheel axles, sills having flanges formed at the bottom thereof, ties 55 between said sills, a floor located below the wheel axles and mounted on said flanges and ties, a longitudinal buffer beam forming a part of said floor, and axle housings mounted on the floor and connected to said sills.

60 6. In a mine car, wheel axles, sills having flanges formed at the bottom thereof, ties between said sills, a floor located below the wheel axles and mounted on said flanges and ties, a longitudinal buffer beam forming a 65 part of said floor, axle housings mounted

on the floor and connected to said sills, and bumpers secured to ends of the floor.

7. In a mine car, wheel axles, journal boxes, a plate sill mounted on the journal boxes on each side of the car, and having a 70 bottom flange, a side floor, a side wall, a central floor mounted on said sill flanges below the wheel axles, a longitudinal buffer beam forming a part of said central floor and belts connecting the buffer beam, central floor, sills, side floors and side walls. 75

8. In a mine car, wheel axles, sills having bottom flanges, sloping side floors, side walls, a central wooden floor mounted on said sill flanges below the wheel axles, and housings 80 for the wheel axles secured to the sills.

9. In a mine car, wheel axles, sills having bottom flanges, sloping side floors, side walls, openings in each side floor for the tops of the wheels, a wheel hood for covering each 85 of said openings, a central wooden floor mounted on said sill flanges below the wheel axles, and housings for the wheel axles secured to the sills.

10. In a mine car, wheel axles, sill plates 90 having bottom flanges thereon below the wheel axles, a floor supported on said sill flanges, and axle housings mounted on said floor and connected to said sills, said housings having a gradual slope on one side 95 thereof.

11. In a mine car, wheel axles, sill plates having bottom flanges thereon below the wheel axles, side floors intersecting the top 100 part of the wheels and carried by the sills, hoods covering the wheel openings in the side floors, side walls carried by the sills, and a central floor carried by the sill flanges below the wheel axles.

12. In a mine car, wheel axles, sills, ties 105 connecting said sills, a longitudinal buffer beam supported on said ties below the wheel axles and forming a portion of the floor, wooden flooring extending from the buffer beam to the sills, a filler block mounted on 110 and above the end of the buffer beam and flooring, and a bumper carried by the floor ing and mounted on said filler block.

13. In a mine car, wheel axles, sills, having bottom flanges thereon, ties connecting 115 said sills, a longitudinal buffer beam supported on said ties below the wheel axles and forming a portion of the floor, wooden flooring extending from the buffer beam to the sills and supported on said ties and the sill flanges, a bumper carried by and secured to the flooring projecting beyond the car body, and a draw bar member projecting through the top of the bumper and connected to said buffer beam. 120

14. In a mine car, wheel axles, sills, ties between said sills, flooring comprising a longitudinal buffer beam and wooden planks carried by said ties and sills below the wheel 125 axles, filler blocks mounted on the flooring 130

- projecting beyond the car body, bumpers, and draw bar members projecting through the top of the bumpers and the filler blocks and connected to the buffer beam.
5. 15. In a mine car, wheel axles, sills having flanges below the wheel axles, ties connecting the flanges on said sills, flooring comprising a longitudinal buffer beam and wooden planks on each side thereof, said 10 flooring being carried by said flanges and ties below the wheel axles and axle housings carried by said flooring and connected to said sills.
16. In a mine car, wheel axles, sills having inwardly turned flanges located below the wheel axles, ties extending between the flanges on said sills, a longitudinal central buffer beam having flanges connected to said ties, axle housings connected to the sills, and 20 wooden flooring mounted on the ties below the housings and between the buffer beam and the side sills, means fixedly securing the ties to the sills and the buffer beam, and means detachably securing the flooring to the 25 housings and ties.
17. In a mine car, wheel axles, plate sills having inwardly turned bottom flanges thereon, sloping side floors and side walls carried by said sills, belts extending around 30 the car from adjacent the top of the side walls below said sills and being connected to the flanges on said sills and to the side floors and walls, and a floor supported on said flanges and belts below the wheel axles.
35. 18. In a mine car, wheel axles, plate side sills having bottom flanges thereon, side floors and side walls carried by said sills, a plate end sill and wall connecting the side sills at one end thereof, a door at the opposite end of the car, a central floor below the wheel axles and carried by said flanges and the end sill, and belts connected to the central floor, the side sills, the side floors and the side walls.
40. 19. In a mine car, wheel axles, journal boxes, plate side sills mounted on said journal boxes and having bottom flanges below the wheel axles, side floors and walls carried by said side sills, belts connecting said side 45 sills side floors and side walls, a central floor 50 carried by said flanges and belts below the wheel axles, and housings for the wheel axles mounted on the central floor and connected to the side sills.
20. In a self-clearing end dump mine car, 55 wheel axles, a longitudinally extending wood flooring comprising the lower most longitudinally extending horizontal member of the car, supporting sills for said flooring, and self-clearing housings over said axles and 60 resting on the wood flooring.
21. In a self-clearing end dump mine car, 65 wheel axles, a longitudinally extending wood flooring comprising the lower most longitudinally extending horizontal member of the car, sills for supporting said flooring, 70 axle housings mounted on said flooring and connected to said sills, and ties between the sills and located below the flooring.
22. In a self-clearing end dump mine car, 75 wheel axles, a longitudinally extending wood flooring comprising the lower most longitudinally extending horizontal member of the car, supporting sills for said flooring, side floors and side walls carried by said sills, 80 self-clearing housings over said axles and resting on the wood flooring and ties connecting the sills.
23. In a self-clearing end dump mine car, 85 wheel axles, side sills carried on said axles, a longitudinally extending wood flooring positioned below the wheel axles and comprising the lower most longitudinally extending horizontal member of the car, said sills carrying said flooring, and ties between said sills.
24. In a self-clearing end dump mine car, 90 wheel axles, a longitudinally extending wood flooring comprising the lower most longitudinally extending horizontal member of the car, supporting sills for said flooring, self-clearing housings over said axles and 95 resting on the wood flooring, said housings being connected to said sills, and ties between the sills and located below the flooring.
- In witness wheroft I have hereunto set my hand.

HENRY P. FIELD.
